DIAMOND POWER SPECIALTY CORPORATION, OF DETROIT, MICHIGAN, A CORPORA-
TION OF MICHIGAN

BOILER CLEANER

Application filed April 28, 1919. Serial No. 293,157.

The invention relates to boiler cleaners of that type in which the blower tube is arranged transversely to a row of boiler tubes and adjacent thereto or between adjacent 5 rows of tubes. The invention consists in the novel construction of bearing which is attached to the boiler tube and which in co-operation therewith positions the blower tube.

10. In the drawings:

Figure 1 is an end elevation and Figure 2 is a side elevation of one construction of bearing;

Figures 3 and 4 are similar views of a modified construction, and

Figure 5 is a fragmentary perspective view of the interlocking ends of the sections of the bearing, showing the same disassembled.

My improved bearing consists essentially 20 of a saddle A of segmental form for embracing one of the boiler tubes B, and a U-shaped or recessed member or element C integral with and projecting from said saddle member for embracing the blower tube D. 25 The U-shaped portion is laterally offset from the saddle portion so that the clamping means for the latter will not interfere with the blower pipe. Thus, as shown, the saddle is clamped by a member or element E having a T-shaped head F for pivotally engaging a slot-

ted bearing G on one side of the saddle member, or element, said member E being of segmental form and passing around the opposite side of the boiler tube and secured by a single 30 clamping bolt H, which passes through aligned apertures in the said elements. When the bearing is clamped to the boiler tube the blower tube may be inserted through the U-shaped slot therein either between rows 35 of tubes B and B', as shown in Figures 1 and 2, wherein it rests upon the lower row of tubes or along the top row of a bank of tubes as shown in Figures 3 and 4 wherein it rests upon this top row of tubes. In either case 40 the support for the blower tube is afforded by the boiler tubes and the bearing merely locates it and prevents lateral displacement.

What I claim as my invention is:

1. In a boiler cleaner, the combination 50 with a boiler tube and a blower tube sup-

ported thereon, of means carried by the boiler tube for maintaining the blower tube in position comprising complementary members having recesses combined to form a pocket receiving the boiler tube, an element 55 projecting from one of said complementary members in a direction substantially at right angles with a plane perpendicular with the boiler tube axis at the point of location of said complementary members, said element 60 having means receiving the blower tube, and means securing the complementary members together and disposed to one side of said element.

2. In a boiler cleaner, the combination with 65 a boiler tube and a blower tube disposed transversely thereof and rotatably supported thereon, of means carried by the boiler tube for restraining the blower tube from moving longitudinally of the boiler tube, said means comprising complementary members having recesses combined to form a pocket receiving the boiler tube, a member projecting from one of said complementary members in the direction of the length of said boiler tube 70 and having means receiving the blower tube, and means securing the complementary members together and disposed on opposite sides of said pocket and to one side of said blower tube receiving means.

3. In a boiler cleaner, the combination with 75 a boiler tube and a blower tube disposed transversely thereof and rotatably supported thereon, of means carried by the boiler tube for restraining the blower tube from moving longitudinally of the boiler tube, said means comprising a saddle member and a clamp member, said members having recesses combined to form a pocket receiving the boiler tube, a member projecting from said saddle 80 in the direction of the length of said boiler tube and having a recess receiving the blower tube, and a clamping bolt acting on said members and disposed to one side of said recess.

4. A bracket for positioning a blower tube adjacent a relatively transverse boiler tube comprising a member having a segmental portion for fitting about the boiler tube and having a blower tube engaging portion transverse 100

to the blower tube and offset from the segmental portion in the direction of the boiler tube, a segmental member cooperating with said segmental portion for oppositely engaging the boiler tube, means establishing interlocking pivotal engagement between said members on one side of the axis of the segments and a single clamping device extending parallel to the axis of the blower tube at one side thereof and engaging said members on the side of said segments diametrically opposite the said pivotal engagement means.

5. A device for retaining a blower tube in position on a boiler tube, comprising a pair of clamping elements provided with aligned apertures and having portions arranged to form complementary walls of a boiler tube receiving pocket, one of said elements formed as a substantially flat member having in one edge a blower tube receiving recess and in its opposite edge an open slot, and means for securing said elements together comprising a bolt detachably received in said apertures and interlocking means disposed substantially opposite said bolt across the pocket, said interlocking means comprising said open slot and a head on the other element received in said slot, said recess being located laterally of the plane of the bolt, whereby a blower tube therein does not interfere with the insertion or withdrawal of said bolt in the assembly of the bracket in operative position or removal therefrom.

6. In a boiler cleaner, the combination with a boiler tube and a blower tube disposed transversely thereof, of means carried by the boiler tube for positioning said blower tube adjacent the boiler tube, said means comprising complementary segmental members having recesses combined to form a pocket receiving the boiler tube, a member projecting from one of said segmental members in the direction of the length of said boiler tube, including means engaging the blower tube to position the blower tube, and means securing the segmental members together and disposed on opposite sides of said pocket and to one side of said blower element engaging means.

50 7. A bracket comprising two members enclosing between them a pocket for receiving a boiler tube and means on opposite sides of the pocket detachably securing said members together, one of said members being provided with a portion disposed adjacent said pocket and forming a positioning means for a blower tube transversely to the pocket, the parts of the bracket being so arranged that when the bracket is applied to a boiler tube, 60 the securing means will be on one side of a plane transverse to said boiler tube and the blower tube positioning means on the other side of said plane.

8. A blower tube positioning bracket adapted to be clamped to a boiler tube, and to en-

gage a blower tube disposed transversely thereof to restrain said blower tube from movement longitudinally of the boiler tube, said bracket comprising a saddle and a clamping member separably united and formed to provide a cylindrical pocket for receiving said boiler tube, a member rigid with said saddle and having a free end projecting therefrom in the same direction as the axis of said pocket, said end being provided with a recess extending to a line substantially tangent with said pocket for receiving the blower tube, and means for securing said saddle and said clamping member in clamping relation on the boiler tube and comprising a bolt, 70 said clamping member and said saddle having apertures therein arranged to one side of said projecting member for receiving said bolt and permitting its insertion in the assembly of the bracket or withdrawal of the bolt without interference by the blower tube.

9. In a boiler cleaner, the combination with a boiler tube, and a blower tube disposed transversely thereof, of means carried by the boiler tube for restraining the blower tube from moving longitudinally of the boiler tube, said means comprising a saddle member and a clamp member, said members having recesses combined to form a pocket receiving the boiler tube, a member projecting from said saddle member in the direction of the length of said boiler tube and having an open recess receiving the blower tube, and means securing the saddle member and clamp member together and disposed on opposite sides of said pocket and to one side of said open recess.

In testimony whereof I affix my signature.
WILLIS P. THOMAS.
